(No Model.)

H. A. RIDLEY.
Shovel Plow Blade.

No. 240,766.

Patented April 26, 1881.

UNITED STATES PATENT OFFICE.

HENRY A. RIDLEY, OF NEWPORT, ARKANSAS, ASSIGNOR TO HIMSELF AND
LAZAR HIRSCH, OF SAME PLACE.

SHOVEL-PLOW BLADE.

SPECIFICATION forming part of Letters Patent No. 240,766, dated April 26, 1881.

Application filed February 2, 1881. (No model.)

To all whom it may concern:

Be it known that I, HENRY A. RIDLEY, of Newport, in the county of Jackson and State of Arkansas, have invented a new Improvement 5 in Shovel-Plow Blades, of which the following is a full, clear, and exact description.

Figure 1 is a front elevation of my improvement. Fig. 2 is a sectional side elevation of the same, taken through the line $x x$, Fig. 1. Fig. 3 is a sectional plan view of the same, taken through the line $y y$, Fig. 1. Fig. 4 is a perspective view of one of the separable wings.

The object of this invention is to facilitate the enlargement and contraction of shovel-plow 15 blades, as the character of the work to be done may require, and also to facilitate repairing the blades.

The invention consists in constructing a shovel-plow blade, of a base plate to be attached 20 to the plow standards to support the sections of the blade, and the changeable wings and changeable point secured to the projecting sides and lower end of the base-plate, whereby the said wings and point, or either of them, can 25 be readily detached and replaced by others of different size or shape, as will be hereinafter fully described.

A is a plate which is designed to be secured to the plow-standard B by bolts C. The lower 30 end of the base-plate A is made pointed, and to the said plate, a little above its lower end, is secured by bolts or rivets a rectangular plate, D, which is made narrower than the said plate A, and has its side and lower edges beveled upon their rear sides, to receive the beveled edges of the wings E and point F. The projecting parts of the base-plate A form

seats for the wings E and point F, which parts E F are secured in place by bolts G.

I have described the base-plate as being 40 made in two parts or pieces and secured to each other; but it is obvious that it can be made in one piece without departing from my invention, the essential feature being to provide shouldered seats to receive and support 45 the changeable parts of the shovel.

With this construction, when the wings E and point F, or either of them, become worn or are broken, they can be readily detached and replaced by other parts or sections, thus 50 avoiding the expense of buying an entire blade. By this construction, also, the wings E can be detached and replaced by larger or smaller wings, as the size of the plants or the work to be done may require.

The wings E can be made pointed, as shown in Fig. 1, or mold-board shaped, as shown in Fig. 4, or of any other desired shape.

Having thus described my invention, what I claim as new, and desire to secure by Letters 60 Patent, is—

The combination, with the plate A, adapted to be secured to any plow-standard and pointed at the lower end, the wings E, and the point F, of the rectangular plate D, placed between the 65 wings E E and in rear of the point F, flush with them all, and overlapping, with a beveled edge, the correspondingly-beveled edge of each of them, as shown and described.

HENRY A. RIDLEY.
